UNITED STATES PATENT OFFICE.

CHARLES W. AXT AND FERDINAND H. BORCHERDING, OF FORT WAYNE,
INDIANA.

CISTERN-COVER.

SPECIFICATION forming part of Letters Patent No. 784,531, dated March 14, 1905.

Application filed July 27, 1904. Serial No. 218,328.

To all whom it may concern:

Be it known that we, CHARLES W. Axt and FERDINAND H. BORCHERDING, citizens of the United States, residing at Fort Wayne, in the county of Allen, in the State of Indiana, have invented certain new and useful Improvements in Cistern-Covers; and we do hereby declare that the following is a full, clear, and exact description of the invention, which will 5 enable others skilled in the art to which it appertains to make and use the same, reference being had to the accompanying drawings, which form part of this specification.

Our invention relates to improvements in 15 covers for cisterns, wells, and catch-basins.

The primary object of our present invention is to provide a cover for cisterns and wells having an interlocking two-part cap detachably mounted on the annular or stationary portion of the cover and having a novel means for rigidly securing the base of the pump-stock in position thereon.

Another object of our invention is to provide a cistern-cover having an interlocking cap which by a slight modification is adapted 25 for use as a cover for catch-basins.

Our invention consists of an annular outer portion or rim having a central circular opening of proper size and a two-part cap detachably mounted on the said annular portion, closing the said central portion, and having an interlocked engagement with the said annular portion and provided with a circular recess adapted to holdingly engage the usual 30 bell-shaped base of the pump-stock in use.

The principal novel features of our invention reside in the means for interlocking the parts of the cap together and to the stationary portion of the cover, and for securing the 35 pump-stock to the cap.

In the drawings similar reference-numerals indicate like parts throughout the several views, in which—

Figure 1 is a vertical central section of 45 our invention, taken on the line $x-x$ of Fig. 4. Fig. 2 is a vertical central section of the same, taken on the line $y-y$ of Fig. 4, showing the relative arrangement of the pump-stock base and suction-pipe when in position therein.

Fig. 3 is a side view of our invention, showing the parts in their interlocked relation. Fig. 4 is a plan view of the same with one of the detachable cap-sections moved out of position to show the means by which the interlocked union is effected and also showing in 55 dotted outline the relative arrangement of the cap-sections when in their interlocked engagement.

The annular portion or rim 1 of the cover has a width corresponding with the thickness 60 of the wall of the well or cistern upon which it is mounted and is provided with two or more pendent anchorage-lugs 2 of any proper form, preferably in opposite arrangement and secured to the supporting-wall in any suitable 65 manner. This annular portion 1 of the cover has a vertical slot 3 upon its inner edge, Fig. 4, and in approximately opposite arrangement it has upon the lower face of its inner edge an undercut recess 4, Fig. 2, for the purpose 70 about to be described.

The cap consists of two separable approximately-equal semicircular sections 5 and 6, having coöperative semicircular openings 7 and 8, respectively, upon their meeting edges 75 to form a central opening for the suction-pipe 19. These cap-sections 5 and 6 are provided upon their upper face with the coincident inclined semicircular flanges 9 and 10, respectively, adapted when the parts are united to 80 form a bell-shaped recess 11, adapted to holdingly secure the flaring base of the pump-stock 12, Fig. 2. The cap-section 6 has upon its diametric edge the opposite duplicate flanges 13, Figs. 2 and 4, adapted to overlap 85 and holdingly engage the corresponding portions of the adjacent edge of the coöperating section 5, as shown in dotted outline in Fig. 4. The cap-section 6 also has upon its lower face at its inner edge and at or near its perimeter 90 the pendent lugs 14 and 15, the former being adapted for an interlocking engagement with the adjacent edge of the annular portion 1 in the recess 4, Figs. 1 and 2, and the latter being adapted to engage the lower face of the 95 portion 1 at one end of the said slot 3 when in position in an undercut recess 20. The cap-section 5 has upon its lower face at or near its

perimeter a pendent lug 16, Fig. 1, adapted to snugly fit in and fill the remainder of the slot 3 when the lug 14 is in position therein. These cap-sections 5 and 6 are provided upon 5 their upper face in opposite arrangement at or near their inner and interlocking edges with the laterally-apertured ears or lugs 17, adapted to be rigidly united by a proper bolt 18 in a well-understood manner. These ears 10 17 are preferably arranged on that portion of the cap-sections which are adjacent to the said slot 4.

The manner of employing our invention thus described is obvious and, briefly stated, 15 is as follows: When the annular portion 1 of the cover has been properly anchored by cement or otherwise upon a well or cistern wall, the two-part cap and pump-stock are united in their holding engagement by first placing the 20 cap-section 6 in its interlocked engagement with the supporting annular portion 1. This is readily and conveniently done by inserting the lug 14 into its holding position, and then doing likewise with the lug 15, which engages 25 the cover portion 1 at the adjacent end of the slot 3, as described. The operator now places the pump-stock 12 in position on the cap-section 6 in such a manner that the flaring or bell-shaped base of the pump-stock is arranged 30 beneath the flange 13, and the suction-pipe 19, which is usually fixed or integral with the pump-stock, is in the opening 8. He next places the other cap-section 5 in position by placing the lug 16 thereon in its position in 35 the slot 3, brings the inner edge of the section 5 into position beneath the flanges 13, and then secures these cap-sections rigidly together by means of the bolt 18. These cap-sections are thus not only locked together, 40 but are rigidly interlocked with the annular plate 1, while at the same time the pump-stock 12 is rigidly secured in position by means of the flanges 10.

When it is desired to employ our invention 45 as a catch-basin cover or like purposes, the flange 10 may be omitted, the central opening may be reduced in size, and additional perforations provided, if desirable.

What we desire to secure by Letters Patent is—

1. A cistern-cover consisting of an annular

metallic rim having a vertical slot and an undercut recess upon its inner edge in diametric relation; a two-part cap for the central opening of the rim, consisting of two 55 separable sections or semicircular plates having coincident semicircular openings at their inner edge, and coincident semicircular inclined flanges concentric with the said cap for the purpose specified, and provided upon their 60 lower face with pendent lugs adapted for an interlocked engagement with the adjacent inner edge of the rim at the said slot and recess; and means for locking the said cap-sections together. 65

2. In a well or cistern cover an annular supporting-rim having its inner edge provided with a vertical slot and an undercut recess in opposite relation; a two-part cover consisting of substantially duplicate semicircular plates 70 having semicircular openings at their inner edge, semicircular inclined flanges upon their upper face for the purpose specified; means for securing the said plates to the said rim; and means for interlocking the said plates together. 75

3. In a cistern or well cover an annular supporting-rim having its inner edge slotted and undercut as shown; a cap for the central opening of said rim consisting of two semicircular 80 plates having coincident semicircular openings at their diametric edge, having coincident semicircular inclined flanges upon their upper face for the purpose specified, one of said plates having on its inner edge flanges 85 overlapping its companion plate and having upon its lower face pendent lugs adapted for an interlocking engagement with the said rim in the said slot and recess respectively, the other plate having upon its lower face a pendent lug 90 adapted to engage the said slot; and means for securing the said plates against lateral displacement when in position. 95

Signed by us at Fort Wayne, Allen county, State of Indiana, this 23d day of July, A. D. 1904.

CHARLES W. AXT.
FERDINAND H. BORCHERDING.
